UNITED STATES PATENT OFFICE.

WILLIAM C. HOMAN, OF MERIDEN, CONNECTICUT, ASSIGNEE TO LEWIS T. WILCOX, OF PEEKSKILL, NEW YORK.

OIL-STOVE BURNER.

Application filed May 1, 1925. Serial No. 27,350.

To all whom it may concern:

Be it known that I, WILLIAM C. HOMAN, a citizen of the United States, residing at Meriden, in the county of New Haven, in 5 the State of Connecticut, have invented an Improvement in Oil-Stove Burners, of which the following is a specification.

This invention relates to a burner particularly adapted for use in oil stoves and similar heat generators. In devices of this type as ordinarily constructed there is included a wick tube, means for raising and lowering a wick within the wick tube, and an air distributor removably associated with the wick tube. It has also been more or less customary in burners of the type to which my invention relates to employ locking devices for maintaining the air distributor in position in its associated relationship with the wick tube, so that by unlocking the said devices the air distributor may be separated and removed from the burner tube. However, so far as I am aware all these locking devices which have been heretofore employed have 25 been more or less complicated, and have also made it extremely difficult to gain sufficiently ready access to the interior of the burner when the air distributor is removed to adequately clean the interior of the 30 burner.

The object of my invention is to overcome these difficulties, and in doing so the invention relates more particularly to devices for normally maintaining the air distributor in 35 position, thereby making it impossible to raise the wick higher than a predetermined point, because of the spreader forming part of the air distributor being fixed in position with the air distributor, and making the interior parts of the burner easily accessible for cleaning purposes when the air distributor is removed. Consequently, in carrying 40 out the invention I employ a plurality of latch devices preferably gravity actuated, and adapted to engage a projection provided for this purpose interiorly of the burner, in order to normally maintain the air distributor in position in association with the other 45 parts of the burner, as will be hereinafter 50 more particularly described.

In the drawing:

Fig. 1 is a sectional elevation illustrating an oil stove burner made in accordance with my present invention.

Fig. 2 is a similar view showing the parts 65 of the burner in another position.

Fig. 3 is a partial elevation of the outer wall of the air distributor, and

Fig. 4 is a fragmentary section on line 69 4-4, Fig. 3.

Referring to the drawing it will be seen that my present invention may be applied to an oil stove or similar burner of a more or less conventional type; such a burner, for example, as illustrated, includes an outer 65 burner tube 10, and an inner burner tube 11, between which the usual wick 12, and the wick holder 13, carrying the same are located, and movable vertically so as to adjust the wick to position by any suitable means. 70

As illustrated, the other burner tube 10, is provided with a rib 14, associated with which are arms 15, for supporting a collar 16; adjacent its lower periphery the collar 16 is provided with a shoulder 17, upon 75 which the base of the casing or body member 18 of the stove rests and is supported.

The burner also includes a suitable air distributor as illustrated. This comprises a drum 19, which is preferably cylindrical, 80 provided with suitably placed apertures 20, for the circulation of air, and is made of any suitable material. This drum 19, is what may be called the outer drum of the air distributor. At its upper end this outer 85 drum terminates in an angular flange 21, terminating in a depending rim 22, adapted to fit within the inner burner tube 11, at the upper end thereof. The air distributor also includes a bottom or base 23, provided with 90 suitable apertures 24, and having a centrally disposed flange 25, within which the lower end of an inner drum 26, is received and suitably secured. This inner drum 26, is also preferably cylindrical, and is provided 95 with a plurality of suitably spaced apertures 27. As illustrated, the inner drum 26, is open at both the top and the bottom thereof, and the drum is sufficiently long to extend appreciably above the top of the burner 100 when the air distributor is in position thereon. At its upper or outer end this inner drum 26, carries a spreader 28, extending over the top of the drum, and sufficiently beyond the same to overlie the wick 12, when the parts 105 of the air distributor are in position. The particular construction of the spreader 28 forms no part of my invention. As illus-

trated however, it is preferably provided with a plurality of apertures 29, in that portion thereof extending immediately over the upper end of the inner drum, and with a plurality of apertures 30, in that portion thereof which extends beyond the inner drum, these apertures being employed for obtaining a desired circulation of the air.

As illustrated the lower or inner portion 10 of the outer drum 19, fits within and is secured to a shoulder 31, provided for this purpose in the base 23, and the peripheral portion of the base 23 preferably comprises a rim 32, adapted when the air distributor 15 is in place to rest upon and be supported by the internal rim 33, or other support, provided for this purpose in the wall of the inner burner tube 11. The parts of the burner hereinbefore described are more or 20 less conventional, and as will be understood may be varied depending upon circumstances, so as to adapt the burner to any particular use.

As hereinbefore stated my present invention relates more particularly to the devices employed for permitting the burner when inserted in position to become automatically locked in place, and to remain so under normal operating conditions, so that for example, the wick cannot be raised more than a predetermined distance before contacting with the spreader member, and also to permit the air distributor to be readily removed to gain ready access to the interior thereof, 25 and the interior burner for cleaning and other purposes. To this end as illustrated, I employ a plurality, preferably a pair, of bell crank levers 34-35. These bell crank levers are similarly constructed and mounted in the same manner in oppositely disposed positions, each comprising a relatively short arm and a relatively long arm; for example, as illustrated the bell crank lever 35, is mounted at the end of its short arm between brackets 36 and 37, cut in, and turned out of the wall of the outer drum 19, this end of the bell crank lever being pivotally connected between these brackets as indicated at 38. On the outer edge of each bell crank lever at the angular portion thereof there is a latch, that on the lever 34, being indicated at 39, and that on the lever 35, at 40; these latches are adapted to engage with the inner or under surface of the internal rib 33. At the extremities of the long arms of the bell crank levers the same are provided with slots, the slot in the lever 34 being designated at 41, and the slot in the lever 35 being designated at 42. The slotted ends 45 of the levers overlap each other as clearly indicated in the drawing, and the end of a rod 43, is passed through the slots and turned or hooked so as to remain in position therein. This rod 43, passes upwardly or 50 outwardly through the inner drum 26, and

through a suitably disposed opening therein, and exteriorly thereof is provided with an eye or ring 45.

The pivotal connections between the short arms of the levers and the brackets in which they are mounted, and the connection between the slotted ends of the levers and the inner end of the rod 43, are sufficiently loose to permit these parts to operate readily and with substantially no friction by slightly 70 spacing the connected parts. It will also be understood that these parts will not be rendered inoperative by becoming clogged or corroded. It will now be apparent that the air distributor may be placed in position in the burner by lifting or holding the air distributor by the ring 45, by means of which the levers are moved to the position shown in Fig. 2, in which the latch points 75 of the levers are moved inwardly sufficiently 80 to clear the internal flange 33. After the peripheral rim of the base on the air distributor reaches its seat on the upper or outer portion of this internal rib the handle or ring 45 may be released, whereupon, automatically and through the action of gravity the long arms of the levers descend or fall to the position indicated in Fig. 1, in which the ring 45 rests upon the top of the spreader 28, and the latch 85 points 39 and 40 of the levers engage beneath the internal rib 33 to normally lock and maintain the air distributor in position in the burner, making it impossible for the wick to be raised for a more than a 90 predetermined distance, that is to say, until it comes in contact with the spreader 28. It will also be apparent that by lifting the ring 45 and raising the rod 43, the bell crank levers 34 and 35 will be swung inwardly by 95 lifting the ends of the long arms thereof, thereby releasing the latch points 39 and 100 40, and permitting the air distributor to be readily removed from the burner. Furthermore, in view of the fact that the internal rib 33 is the only projection extending within the burner, and the other fact 105 that this is relatively small there are no objectionable obstructions within the interior of the burner, and when the air distributor is removed, the same, and the interior 110 of the burner may be readily cleaned.

I claim as my invention:

1. In an oil stove burner, burner tubes, a wick associated with the same, an air distributor, a pair of bell crank levers, each having a latch thereon, means for pivotally connecting the bell crank levers at corresponding ends thereof at oppositely disposed points on the exterior of said air distributor, means associated with the inner wick tube to be engaged by the said bell crank levers for normally maintaining the air distributor in position in the burner, and means for connecting the other ends of the bell crank 120 125 130

levers for moving and freeing the same to release the said air distributor.

2. In an oil stove burner, burner tubes, a wick associated with the same, an air distributor, a pair of bell crank levers each having a latch at the angular portion thereof, means for pivotally connecting the bell crank levers at corresponding ends thereof to oppositely disposed points on the exterior 10 of the air distributor, means associated with the wick tube to be engaged by the latches at the angular portions of the said bell crank levers for normally maintaining the air distributor in position, and devices for 15 connecting the other ends of the bell crank levers for moving and freeing the same to release the said air distributor.

3. In an oil stove burner, burner tubes, a wick associated with the burner tubes, an 20 air distributor, a pair of bell crank levers each having a latch at the angular portion thereof, means for pivotally connecting the bell crank levers at corresponding ends thereof to oppositely disposed points on the exterior 25 of the air distributor, an internal flange in the said wick tube adapted to be engaged by the latches at the angular por-

tions of the bell crank levers for normally maintaining the air distributor in position, and devices for connecting the other ends of 30 the bell crank levers for moving and freeing the same to release the said air distributor.

4. In an oil stove burner, burner tubes, a wick associated therewith, an air distributor adapted to be received within the inner 35 burner tube, a pair of bell crank levers having arms of different lengths, means for pivotally connecting the ends of the short arms of the bell crank levers with the said air distributor, the long arms of the said bell 40 crank levers extending beneath the air distributor and overlapping each other, an internal rib on the inner burner tube adapted to be engaged by the said bell crank levers to normally maintain the air distributor in 45 position in the burner, and means for connecting and moving the overlapping ends of the long arms of the bell crank levers for freeing the bell crank levers from the internal rib and lifting the air distributor 50 from the burner.

Signed by me this 9th day of March, 1925.

WILLIAM C. HOMAN.
